UNITED STATES PATENT OFFICE

114,516

DESIGN FOR A NECKLACE

Katharine M. Dick, Clayton, Mo.

Application January 7, 1939, Serial No. 82,218

Term of patent 3½ years

To all whom it may concern:

Be it known that I, Katharine M. Dick, a citizen of the United States, residing at Clayton, county of St. Louis, State of Missouri, have invented a new, original, and ornamental Design for a Necklace, of which the following is a specification, reference being had to the accompanying drawing, forming part thereof.

The figure is a plan view of a necklace, showing my new design.

The design comprises a necklace composed of a plurality of twisted-together strands each of which is composed of a large number of fibrous strings, the ends of the necklace being in crossed and extended relationship.

I claim:

The ornamental design for a necklace, as shown and described.

KATHARINE M. DICK.
